UNITED STATES PATENT OFFICE

LOUIS V. ARONSON, OF NEWARK, NEW JERSEY, ASSIGNOR TO ART METAL WORKS, INC., OF
A CORPORATION OF NEW JERSEY

COMBINED SAFETY RAZOR AND SHARPENING DEVICE

Application filed May 21, 1931. Serial No. 538,936.

This invention relates to improvements in combined safety razors and sharpening devices.

Among the objects of this invention are 5 the provision of improved means facilitating the honing or stropping of opposite faces of the edge of a single edged razor blade, or the opposite faces of the edges of a double edged razor blade without dismounting the razor 10 blade from the razor.

Another object of this invention is the provision of means for holding the razor blade assembled with an outer clamping cap.

Another object of this invention is the arrangement of the improved combination of means facilitating the honing or stropping of both faces of an edge of a razor blade, at an angle with respect to the handle so that the razor blade will assume the proper angular 20 shaving position with respect to the handle.

Another object of this invention is the provision of means for holding a sharpening means in a position in which it does not interfere with the shaving operation.

25 Another object of this invention is the provision of means for holding a sharpening means in the positions it occupies when employed to hone or strop opposite faces of an edge of the razor blade.

30 Other objects of the invention will appear from the following description taken in connection with the drawings, in which

Fig. 1 is a longitudinal section through the handle and transversely of the sharpening means, guard, razor blade and clamping plate, with the razor blade in shaving position and the sharpening means in position to sharpen hone or strop the lower or rear face of one edge of the razor blade;

40 Fig. 2 is a similar section with the outer clamping member and razor blade lifted, shown in the process of being turned to reverse the edges of the blade with respect to the guard and sharpening means;

45 Fig. 3 shows the sharpening means in position to hone or strop the upper face of an edge of a razor blade;

Fig. 4 is a top plan view partly in section, of the device of Fig. 2;

50 Fig. 5 is a view of a device similar to that

of Fig. 1 but showing provision for flexing the razor blade and also means for supporting the sharpening roller so that it may be swung into position to hone or strop each 55 face of an edge of the blade;

Fig. 6 is a cross section on the line 6—6 of Fig. 5;

Fig. 7 is a section on the line 7—7 of Fig. 6;

Fig. 8 illustrates another modified form 60 showing the razor head disposed at an angle to the handle; and

Fig. 9 is a section on the line 9—9 of Fig. 8.

The embodiment shown in Figs. 1, 2, 3 and 4 comprises a hollow handle 10 which at 65 its upper end carries a guard member 11 which has a substantially straight outer face, on one side edge of which are formed curved guard fingers 12. The other edge is preferably cut away on an arc to permit the sharpening roller 13 to be moved into engagement

with the razor blade 14 for the purpose of honing or stropping the lower face of the adjacent edge of the razor blade. The roller 13 is mounted on a shaft 15 suitably journaled 70 in arms 16 of a yoke-like member, the cross member of which is indicated at 17. The yoke member is pivotally supported by means of studs 18 in ears 19 formed or secured to the guard member 11, as is clearly shown in 75 these figures. The center of the studs 18 lies in the plane of the razor blade 14 so that the roller, when in either of the positions shown in Figs. 1 and 3, will bear the proper relation to the adjacent face of the edge of 80 the razor blade. During shaving operations the roller will preferably be in the position shown in Fig. 1, in which position also it may be employed to hone or strop the lower 85 face of the idle edge of the razor blade. The roller may be moved out of engagement with either face and into engagement with the other face of the edge of the blade by manipulating the cross member 17. In Fig. 3 the roller is shown in position to hone or 90 strop the upper face of the edge of the razor blade.

The razor blade may be provided with three apertures, the outside pair of apertures receiving alining studs 20 on the clamp- 100

ing cap 21. The inner stud 22 carried by the clamping cap 21 engages the central opening in the razor blade. One or more of these studs are preferably tapered at the inner end 5 so that when the razor blade is forced on to the studs the resulting frictional engagement will be sufficient to prevent the blade from dropping off the clamping cap when removed.

The stud 22 is provided with a reduced 10 threaded portion 23 which is engaged by an enlarged internally threaded head 24 of a plunger 25 movable within the hollow handle 10, said plunger 25 being normally pressed downwardly, as shown in Fig. 1, by means 15 of the spring 26 which bears against a shoulder in the handle 10 and against a shoulder on a finger piece 27 which may be rigidly secured to the plunger 25 by a rivet or screw, as indicated. When pressure is applied on 20 the finger piece 27 the spring 26 yields and the razor blade and cap may be moved upwardly, as indicated in Fig. 2, after which the cap and razor blade may be rotated so as to reverse the edges of the blade with respect 25 to the guard and sharpening roller 13.

As shown in Figs. 1, 2 and 3, the movement 30 of the plunger 25 with respect to the cap 21 is preferably limited by a shouldered engagement between the stud 22 and the enlarged head on the stem 25, the relation of the same to the clamping cap 21 being such that the blade will be straight and in an unflexed condition when held against the guard member 11. To remove the blade it is merely 35 necessary to unscrew the stud 22 from the piece 24 by turning the finger piece 27, whereupon the cap piece 21 will drop off together with the blade. Then any slight jarring of the cap will release the blade therefrom.

40 In the modification shown in Fig. 5, the guard member 30 is curved and the shoulders on the stud 31 and the head 32 of the plunger 33 are so located and arranged with respect to the clamping cap 36, that by turning the 45 plunger 33 by means of the finger piece 34 the blade 35 may be flexed as the blade is forced into the arcuate clamping cap 36. The sharpening roller 37 is supported on a shaft 38 whose ends are rounded, as indicated at 50 39, exteriorly of the arms 40 supporting the roller. The arms 40 are pivotally supported by means of studs 41 in ears 42 which are formed on the guard member 30 in such a manner as to support the studs 41 in the 55 plane of the exposed edge of the razor blade. When the roller is swung into the position shown in Figs. 5 and 6, the ends 39 of the shaft 38 engage in recesses 43 in the ears 42 to retain the roller in the approximate position shown in Fig. 5. As shown in Fig. 7, the 60 recesses 43 are preferably made on a longer arc than the rounded ends 39 of the shaft 38 in order that the movement of the sharpening roller toward the razor blade may not be limited.

Fig. 8 shows another modification in which the part 45, that corresponds to the handles in the other modifications, is made shorter and the handle proper, as at 46, is secured thereto in an angular relation so that the razor blade 47 bears a proper angular shaving relation to the handle 46. In other respects this construction is the same as that shown in Figs. 1, 2, 3 and 4 except that the sharpening roller 48 is preferably mounted on arms 49 similar to the arms 40 shown in Figs. 5 and 6, and that the sharpening roller is held in each of its moved positions by a different means. The means comprises a projection 50 on each of the arms 49 adapted to engage the proper recess 51 in a supporting ear 52 when the roller is in the position shown in Fig. 8 or in a position corresponding to that shown in Fig. 3.

While the invention has been described in particularity with reference to the several embodiments shown, it is to be understood that other forms or embodiments may be apparent to those skilled in the art after understanding the embodiments herein disclosed, and that it is the intention to include all such embodiments within the terms of the appended claims.

What I claim is:

1. The combination in a razor, a handle, means on said handle for holding a flat razor blade in unflexed condition in position for shaving, a sharpening roller, arms supporting said roller, and pivots for said arms located in the plane of said blade, providing for movement of said roller for cooperative engagement with either face of said razor blade while said razor blade remains held in position for shaving.

2. The combination in a razor, a handle, means on said handle for holding a flat razor blade in unflexed condition in position for shaving, a sharpening device, and means supporting said sharpening device providing for movement of said sharpening device for cooperative engagement with either face of said razor blade while said razor blade remains held in position for shaving.

3. The combination in a razor, a handle, means on said handle for holding a razor blade in curved condition in position for shaving, a sharpening device, and means located in the plane of the edge of said razor blade for supporting said sharpening device for movement into cooperative relation with either face of the edge of the blade, while said blade remains held in position for shaving.

4. The combination in a razor, a handle, means on said handle for holding a razor blade in position for shaving, a sharpening roller, arms supporting said roller for movement into cooperative relation with either face of the edge of said blade while said blade remains held in position for shaving, and a

cross member connecting said arms and constituting a manipulative portion for moving said roller.

5. The combination in a razor, a handle, means on said handle for holding a razor blade in position for shaving, a sharpening roller, arms supporting said roller for movement into cooperative relation with either face of the edge of said blade while said 10 blade remains held in position for shaving, a cross member connecting said arms and constituting a manipulative portion for moving said roller, and means on said arms and razor for holding said roller in approximately the 15 location in which it cooperates with the rear face of the edge of the blade.

6. The combination in a razor, a handle, means on said handle for holding a razor blade in position for shaving, a sharpening 20 roller, arms supporting said roller for movement into cooperative relation with either face of the edge of said blade while said blade remains held in position for shaving, a cross member connecting said arms and constituting 25 a manipulative portion for moving said roller, and means on said arms and said razor for holding said sharpening device in substantially the positions in which it cooperates with the faces of the edge of the blade.

30 7. The combination with a razor including a guard member, a razor blade, means for supporting said blade mounted for movement to carry said blade into cooperative position with the guard member and 35 out of cooperative position and to turn about an axis perpendicular to the plane of the blade, a sharpening device, and means for supporting said sharpening device for movement into cooperative relation with either 40 face of the edge of the blade after it has been turned.

8. The combination in a razor, a razor head, a guard member on one side of said head, a tubular member rigid with and extending substantially perpendicularly to said head and guard, a handle rigid with and extending at an angle to said tubular member, a razor blade clamping plate, a plunger secured to said clamping plate and rotatably 45 50 and slidably mounted in said tubular member and having its free end accessible at the free end of the tubular member for moving a razor blade carried by said clamping plate away from said guard and for rotating said blade, 55 and a sharpening roller pivotally mounted on the opposite side of the head for movement into cooperative relation with either face of a razor blade supported on said head after said blade has been rotated.

60 9. The combination in a razor, a handle, a razor head, a guard on said head, means for holding a doubleedged razor blade on said head with one edge in cooperative relation to said guard, a sharpening device, and means sup- 65 porting said sharpening device for movement

into and out of cooperative relation with either face of the opposite edge of a razor blade while said razor blade remains held in cooperative relation with said guard for shaving.

10. The combination in a razor, of a razor head, means for holding a razor blade on said head in position for shaving, a sharpening device, and means supporting said sharpening device providing for movement of said sharpening device for cooperative engagement with either face of said razor blade while said razor blade remains held stationary on said head by said blade holding means.

11. In a combined razor and sharpening device, a razor head, a guard on one side of said head, a sharpening device on the opposite side of said head, means for holding a razor blade on said head with its edge in cooperative relation to said guard, a handle secured to said head at an angle to the normal of a razor blade held on said head, means providing for movement of said holding means and said blade away from said head and for rotation of said blade to present its edge to said sharpening means, and means supporting said sharpening means providing for movement of said sharpening means into cooperative relation with either face of said edge after said razor blade has been rotated.

12. In a combined safety razor and sharpening device, a handle, a seat connected to said handle supporting a razor blade in position for shaving, a sharpening device, means for supporting said sharpening device, and a connection between said supporting seat for said razor blade and the supporting means for said sharpening device facilitating movement of said sharpening device with respect to a razor blade on said seat for establishing a cooperative relationship between the sharpening device and either face of the edge of the razor blade while the razor blade remains supported on said seat in position for shaving.

In testimony whereof I have signed my name to this specification.

LOUIS V. ARONSON.
